UNITED STATES PATENT OFFICE.

JAMES B. HOGE, OF CLEVELAND, OHIO.

RAILWAY-CONSTRUCTION MACHINERY.

1,108,578.

Specification of Letters Patent. Patented Aug. 25, 1914.

Application filed October 13, 1911. Serial No. 654,526.

To all whom it may concern:

Be it known that I, JAMES B. HOGE, a citizen of the United States, residing at Cleveland, in the county of Cuyahoga and State of Ohio, have invented certain new and useful Improvements in Railway-Construction Machinery, of which the following is a specification, reference being had therein to the accompanying drawing.

10 My invention relates to railway construction machinery, and has for its object the production of a machine adapted to travel along a railway rail and exert pressure upon the rail fastening devices or other parts at 15 points where the same may be required.

In order to attain my object, I provide a saddle frame with a pair of rollers adapted to run along the rail, a pair of vertically movable clamps on opposite sides of the saddle, and one or more compression devices with suitably shaped heads for exerting pressure at any point.

20 My machine is well adapted to operate upon the rail clips described in Letters Patent No. 993,176, granted May 23, 1911, to Henry Kohlmyer, and will be described herein in connection therewith. It should be understood however that such use is not exclusive, and that I contemplate the employment of the machine for other purposes 25 as well as modifications in the machine for the same purpose.

My invention is illustrated in the accompanying drawings in which—

30 Figure 1 is a plan view of the machine, Fig. 2 is a side view, Fig. 3 is an end view, and Fig. 4 is a detail view of a modification showing eccentric bushings for adjusting the shafts 5 and 6 so as to raise and lower 35 the saddle on the rail.

Referring to the drawings, the saddle frame comprises drop members 1, 2, 3 and 4, connected across the top by throughbolts or shafts 5 and 6 carrying wheels 7 and 8, 40 having double flanges with an intermediate tread wide enough to span the head of the rail. The shafts 5 and 6 are threaded on their opposite ends and provided with nuts 5^a, 6^a, 5^b, 6^b. The drop members 1—2 and 45 3—4 are connected in pairs on opposite sides of the saddle by throughbolts 9 and 10, which furnish between the members 1 and 2 pivotal bearings for levers 11 and 12. These 50 levers are provided respectively with shanks 11^a and 12^a which are adapted to receive the 55 sockets 11^b and 12^b on the handle members

11^c and 12^c, which may be detached when the machine is not in use; and on their opposite ends the stub levers 11 and 12 are provided with noses 11ⁿ and 12ⁿ respectively 60 properly shaped and proportioned to exert pressure in the manner and to the extent required. In Fig. 3 the nose on the stub is shaped properly to bend down and flatten the Kohlmyer clip, having a rounded portion 65 11^p and a flat 11^f for the finish.

When bending down the Kohlmyer or similar clips, or when forcing in a spike, or in any similar operation, it is necessary to have an upward grip on the rail or its clip, 70 or on the supporting plate, in order to steady the device and give a firm leverage for the application of power. This is secured by the vertically sliding spindles 13 and 14, each of which is provided at its upper end with a handle 13^a and 14^a, and lock-nuts 13^b and 14^b respectively. Each of these spindles is provided at its lower end with a laterally extending foot 13^f and 14^f, which can be swung around by rotating the spindle 75 into the position shown in the drawings, or out of said position (when the nuts 13^b and 14^b are loosened) so as to clear the ties, whereby it can be raised by drawing up the spindle vertically to permit travel of the 80 machine.

In the drawings the section of rail is represented at R in each figure, having a head r, a foot r' and a web r². A metal tie is shown at T, having a head, foot and web 90 marked t, t' and t² respectively. A Kohlmyer clip is shown in position at C, with its ends c, c' about to be bent by the noses 11ⁿ and 12ⁿ on the stub levers 11 and 12.

The operation of the machine is as follows: The rail R is laid on the cross ties T, and the machine is started at one end and moved from tie to tie, setting up the clips in succession. At each tie the machine is stopped, the levers 11 and 12 are raised into 95 the position shown in Fig. 3, a clip C is inserted from beneath, the spindles 13 and 14 are dropped and turned so as to bring the feet 13^f and 14^f under the clip, this requiring a diagonal position of the feet as shown in Fig. 100 1; the nuts 13^b and 14^b are then given a turn to bring the feet 13^f and 14^f up hard against the clip, and the levers 11 and 12 are then forced down around their pivots, which 105 operation first bends in the ends c, c' of the 110 clips, and then flattens them down firmly against the foot flanges r' of the rail. It

will be observed that as the levers start to force the ends c , c' inward, the point of engagement of these ends is much nearer to the pivotal center of each lever than after the bending has progressed through a certain distance. As in all cold bending, the steel of the clips offers a very high resistance in the beginning, but after once yielding, the bend may be continued smoothly until it is finished by the flat face 11^f with a relatively less leverage than at the start. As soon as the clip shown is properly bent down the levers are again thrown up, the nuts 13^b and 14^b are loosened, the handles 13^a and 14^a are turned to swing the feet 13^f and 14^f out from beneath the tie flange, and then raised so as to clear the ties entirely, and the machine is moved along to the next tie in order, where the same operation is repeated.

20 It will be understood that the members 13^f and 14^f will serve to draw the tie up to and in contact with the bottom of the rail base, should the tie rest in a position below the plane of the rail, and the machine operates to clamp not only the rail and tie together, but also to clamp the clip or fastener C in place preparatory to the bending of the ends of the latter into engagement with the rail base.

30 In Fig. 4, a modification in the form and arrangement of the through bolts for axles for the wheels of the truck or saddle frame is shown. The modified bolt 6 in Fig. 4, has a head 6^b at one end and a nut 6^a threaded on the other end, and the headed end of the bolt has a handle 6^h . By taking off the nut, and grasping the handle, either spindle may be withdrawn, and this permits wheels of different sizes to be employed so as to adapt the machine to rails of different depths. The adjustment of the nuts 13^b and 14^b on the upper ends of the spindles 13 and 14 allows the feet 13^f and 14^f a certain range of adjustment, but this is limited by the necessity for clearing the ties when the feet are drawn up. By providing wheels of different sizes, and making the bolts or shafts so they can be readily withdrawn, as shown in Fig. 4, a still greater variation is attainable. In addition to this I provide eccentric bushings 6^d at each end of the bolt or wheel axle and each bushing is provided with a handle for the purpose of adjusting it into any desired angular position. The combined effect of these three adjustments, viz. the spindle, the wheel, and the bushings, is to make one machine applicable without any other change to all rails likely to be used in the same system. It should be understood of course that the shape and arrangement of the rollers 7 and 8 are variable so as to adapt them to different rails, the rollers shown being especially designed for an ordinary T-rail.

65 There are numerous other changes which

may be made in non-essential features without departing from the invention, and it is to be further understood that I contemplate all such changes and modifications as fairly fall within the scope of the appended claims.

Having thus described my invention what I claim and desire to secure by Letters Patent is—

1. A machine of the class described comprising a frame arranged to rest upon the head of a rail, a clamping member having a substantially horizontal anvil face connected with said frame, a fastener securing device also connected to said frame and arranged to exert pressure against said anvil through a fastening device interconnecting the crossing portions of rails and ties, one of the said coöperating elements having both vertical and lateral movement with respect to the supporting frame whereby it may be lowered between the ties and moved laterally into position beneath the lower end of the fastener.

2. A machine of the class described comprising a frame arranged to rest upon the head of a rail, a clamping member having an anvil face connected with said frame and having both vertical and lateral movement with respect thereto whereby it may be lowered between the ties and moved laterally into position beneath the lower end of fastenings extending between the crossed portions of rails and ties, and a fastener securing device connecting with said frame in co-operative relation to said clamping member and arranged to compress a fastener between itself and the said anvil member.

3. A machine of the class described comprising in combination the following elements arranged symmetrically with respect to the longitudinal vertical plane of the rail, a traveler arranged to bear upon the head of a rail, clamping devices supported from said traveler one on each side thereof and each provided an anvil member having both vertical and lateral movement with respect to said traveler whereby it may be lowered between the ties and moved laterally into position beneath the lower portion of a fastener extending between a crossed rail and tie, and fastener securing devices connected with said traveler one on each side thereof in co-operative relation to the corresponding clamping device and arranged to compress a fastener between itself and the said anvil member.

4. A machine of the class described comprising a supporting frame arranged to rest upon the head of a rail in substantially fixed lateral position, and clamping means connected therewith and provided with a laterally projecting substantially horizontal clamping face having both vertical and lateral movement whereby the same may be lowered and moved laterally into a clamping

position beneath a portion of a tie, together with actuating devices arranged to impart said movements to the clamping means.

5. A machine of the class described comprising a structure for clamping a rail and tie together and simultaneously holding a fastener in applied position to the clamped parts, and means on the structure for forming the fastener into tie and rail holding 10 shape, together with means for supporting the same from the rails.

6. A pressure device for railway construction, comprising a supporting frame adapted to travel on a rail, with an anvil 15 clamp and a direct pressure device carried on said frame, said clamp comprising a vertically adjustable spindle or shaft with a laterally projecting foot adapted to be swung into and out of working position to 20 permit travel of the machine on the rail.

7. A machine of the class described comprising a structure adapted to be supported on a rail and to be moved therealong, means on the structure for clamping a tie to the 25 rail and for holding a fastening in applied position, and means for bending the ends of the fastener into shape for holding the rail and tie together.

8. A machine of the class described comprising a structure adapted to straddle and 30 rest on a rail, members independently mounted on the structure and disposed at opposite sides of the rail for engaging under and clamping a tie to the rail and for holding 35 a fastener in applied position, devices on the structure for shaping the fastener to hold the rail and tie together, said members being independently adjustable on the said structure.

40 9. A pressure machine for forming rail clips comprising the following instrumentalities: a saddle frame provided with a roller traveling on the track rail, a vertically adjustable drop spindle in said frame, 45 with a laterally extending foot forming a pressure clamp adapted to engage beneath the clip when in position, and a pressure device carried on the frame adapted to engage the upper portion of the clip and compress 50 and form the same between itself and said pressure clamp.

10. A pressure machine for forming rail clips comprising the following instrumentalities: a saddle frame comprising cross 55 members and side drop members, with a pair of rollers carried on the cross members and adapted to travel tandem on the track rail, a vertically adjustable spindle having a laterally projecting foot forming a pressure clamp adapted to be adjusted beneath 60 and to engage a clip when in position, and a lever pivoted on the frame so as to lie above and in line with the pressure clamp when so adjusted, said lever having a pressure nose adapted to engage and form the 65

clip by compression between itself and said pressure clamp.

11. A machine for holding two cross members together and applying a fastener thereto, comprising a structure adapted to 70 straddle one of the members, movable elements on the structure having feet extending inwardly under both members where they cross and engaging the fastener, means for exerting power on the structure and elements to clamp the members and fastener 75 together, and devices mounted on the structure for operating on the fastener to secure the members together.

12. A machine for applying a fastener to 80 superimposed cross members, comprising a structure supported by the upper member and movable along the same, devices on the structure adjustable to a position to clear the lower member for permitting the structure to move along the upper member and adjustable to a position to engage under a portion of the lower member and retain a fastener in position, and means mounted on the structure for shaping the fastener to 85 secure the members together.

13. In a fastener applying machine of the class described, the combination of a through bolt forming an axle, a roller thereon, drop members on the bolt, longitudinally adjustable spindles in the drop members, and a fastener engaging foot on each spindle.

14. In a fastener applying machine of the class described, the combination of a through bolt forming an axle, a roller thereon, drop 100 members on the bolt, longitudinally adjustable spindles in the drop members, a fastener engaging foot on each spindle, and a fastener shaping means mounted on each drop member.

15. In a fastener applying machine of the class described, the combination of a pair of bolts, drop members on the bolts, bolts passing through the drop members, fastener-shaping devices movably mounted on the 110 last-mentioned bolts, rail-engaging means on the first-mentioned bolts, and fastener-engaging devices mounted on the drop members.

16. In a fastener applying machine of the 115 class described, the combination of a saddle frame having at each side a pair of drop members connected together at their lower ends, fastener-bending means mounted between each pair of members, and means carried by the saddle frame for holding the fastener in applied position.

17. In a fastener applying machine of the class described, the combination of a saddle frame, a pair of longitudinally movable 120 spindles mounted thereon, fastener engaging feet on the spindles, and means mounted on the frame and disposed above the feet for imparting the final shape to the fastener held by the said feet.

18. In a fastener applying machine of the class described, the combination of a saddle frame having tubular members, spindles rotatably and longitudinally movably mounted in the members, a fastener-engaging device on each spindle, and fastener securing means mounted on the frame in coöperative relation with the said fastener-engaging devices. 70
19. In a fastener applying machine of the class described, the combination of a saddle frame having tubular members, spindles rotatably and longitudinally mounted in the members, a fastener-engaging device on each spindle, fastener shaping means mounted on the frame in coöperative relation with the said fastener-engaging devices, and a rail-engaging roller mounted between said members. 75
20. A fastener applying machine of the class described comprising a saddle frame consisting of spaced tubular members and a through bolt connecting the members together, a roller mounted on the bolt and disposed between the members, and rotatable spindles in the tubular members having fastener-engaging means on the projecting ends of the spindles. 80
21. A fastener applying machine of the class described comprising a saddle frame consisting of spaced tubular members and a through bolt connecting the members together, a roller mounted on the bolt and disposed between the members, rotatable spindles in the tubular members having fastener-engaging means on the projecting ends of the spindles, and fastener shaping devices mounted on the members at a point between the said roller and fastener engaging means. 85
22. In a fastener applying machine of the class described, the combination of a saddle frame comprising a pair of drop members at each side, one member of each pair being tubular, a rotatable and longitudinally movable spindle in each tubular member and having a fastener-engaging means, and fastener shaping devices mounted between each pair of members. 90
23. A fastener applying machine of the class described comprising a saddle frame having depending side sections counterbalancing each other, and a plurality of rail-engaging rollers disposed between the sections and centrally thereof, fastener-engaging devices on the said sections, and fastener shaping devices also on said sections. 95
24. A fastener applying machine of the class described comprising a saddle frame having a supporting traveler arranged to support the frame in travel along the rail, fastener supporting devices on the frame, and means for adjusting the position of the axis of the traveler with respect to the frame, together with a fastener securing device arranged upon the frame to act upon a fastener and to secure the same in place. 100
25. A fastener applying machine of the class described comprising a saddle frame having a supporting traveler arranged to support the frame in travel along the rail, fastener supporting devices on the frame, means for adjusting the position of the axis of the roller with respect to the frame, and means for adjusting the said devices on the frame. 105
26. A fastener applying machine of the class described comprising a frame including a shaft, and a rail-engaging traveler on the shaft arranged to support the frame for travel along the rail, eccentrics in which the shaft is mounted for adjusting the position of the axis of the traveler, and fastener-engaging devices on the frame. 110
27. A fastener applying machine of the class described comprising a frame including a shaft, a rail-engaging roller on the shaft, eccentrics in which the shaft is mounted for adjusting the position of the axis of the roller, fastener-engaging devices on the frame, and means for adjusting the said devices toward or from the roller. 115
28. A machine of the class described comprising an axle, drop members on the ends thereof, eccentric bushings in the members and through which the axle extends, and a track engaging roller on the axle and disposed between the members, and fastener-engaging devices mounted on the members and adjustable toward or from the roller. 120
29. A machine of the class described comprising a frame arranged to be supported upon a rail, a pair of rotatably and vertically movable members supported therefrom, fastener engaging devices thereon, and fastener shaping devices mounted in coöperative relation with the first mentioned devices. 125
30. A machine of the class described comprising a frame arranged to be supported upon a rail, devices mounted on the frame and moving rectilinearly up and down, and curvilinearly into and out of engagement with a fastener to be applied, and fastener shaping elements disposed in coöperative relation with said devices. 130
31. In a machine of the class described, the combination of a supporting structure, rotatably and longitudinally movable spindles therein, fastener engaging feet on the spindles, and levers fulcrumed on the structure above the feet and having fastener shaping noses extending toward the feet. 135
32. A machine of the class described comprising a pair of bolts, rollers thereon, depending members on the ends of the bolts, bolts extending transversely to the first mentioned bolts and each connecting a pair of members together, and fastener shaping devices mounted on the last-mentioned bolts. 140
33. A machine of the class described comprising a frame arranged to rest upon the 130

head of a rail, a clamping member for a fastener and a fastener securing device connected with said frame in coöperative relation and arranged for the compression of a fastener between them, one of said members having both vertical and lateral movement with respect to said frame, whereby it may be lowered between the ties and moved later-

ally into a position to engage the under portion of a fastener.

In testimony whereof I affix my signature in presence of two witnesses.

JAMES B. HOGE.
